Patented May 25, 1976

240,008

MINIATURE VACUUM CLEANING TOOL OR THE LIKE

William S. Fortune, 14250 Dearborn St.,
Panorama City, Calif. 91402

Filed June 24, 1974, Ser. No. 482,222

Term of patent 14 years

Int. Cl. D8—05

U.S. Cl. D8—51

Fig. 1

Fig. 2

Fig. 3

Fig. 4

FIG. 1 is a side elevational view of a miniature vacuum cleaning tool or the like in an uncocked position showing my new design;

FIG. 2 is a similar view thereof, but shown in a cocked position;

FIG. 3 is a rear view thereof; and

FIG. 4 is a front view thereof.

I claim:

The ornamental design for a miniature vacuum cleaning tool or the like, substantially as shown and described.
